UNITED STATES PATENT OFFICE.

RAYMOND G. BULLOCK, OF JAMESTOWN, NEW YORK, ASSIGNOR TO ART METAL CONSTRUCTION COMPANY, OF JAMESTOWN, NEW YORK, A CORPORATION OF MASSACHUSETTS.

COMPRESSOR FOR FILING-DRAWERS.

1,112,357.

Specification of Letters Patent. Patented Sept. 29, 1914.

Application filed September 17, 1913. Serial No. 790,316.

To all whom it may concern:

Be it known that I, RAYMOND G. BULLOCK, a citizen of the United States, residing at Jamestown, in the county of Chautauqua and State of New York, have invented certain new and useful Improvements in Compressor for Filing-Drawers, of which the following is a specification.

The object of this invention is to provide 10 a new and improved form of compressor for filing drawers.

Another object of this invention is to make the compressor operable from without the drawer, so that the compressor may be 15 operated whether the drawer is opened or closed.

Another object of this invention is to construct a compressor so that it can adjust 20 itself to the volume of sheets or papers that are within the drawer and exert a yielding pressure on them.

Another object of this invention is to construct a compressor so that it may be used in connection with any of the compressors 25 heretofore constructed, this compressor being used at the front of the drawer, the other compressors being used at the rear of the drawer.

These and other objects of my invention 30 will be fully illustrated in the drawings, described in the specification and pointed out in the claims at the end thereof.

In the accompanying drawings, Figure 1 is a front elevation of a case containing a 35 drawer equipped with my improved compressor. Fig. 2 is a vertical section on the line 2^x—2^x of Fig. 1. Fig. 3 is a vertical section on the line 3^x—3^x of Figs. 2 and 4. Fig. 4 is a horizontal section on the line 4^x—4^x of 40 Figs. 2 and 3. Fig. 5 is a vertical section on the line 5^x—5^x of Figs. 3 and 4, showing the compressor and the toggles for operating it. Fig. 6 is a perspective view of the sliding member operated by the handle of 45 the drawer. Fig. 7 is a perspective view of the channel operated by the sliding member. In the accompanying drawings, like reference numerals refer to like parts.

In the drawings, reference numeral 1 indicates any filing case in which is contained 50 a drawer 2. On this drawer are the brackets or lugs 3 and 4 in which is pivotally mounted a handle 5. This handle has the levers 6 and 7 thereon, the inner ends of which 55 project inside of the drawer. Mounted in

the inner ends of the levers 6 and 7 is the pin 8, the outer ends of which pin engage with slots 9 and 10 in the sliding member 11. This sliding member is channel shaped and the lower inner ends of it are cut free from the front part of the channel and are bent in for a purpose that will presently appear. The sides are finished with rounded projections 61, 61 which will make a snug sliding fit with the channel 12 with a minimum 65 friction.

The sliding member 11 is mounted to move in the sliding channel 12 which channel is shown in perspective in Fig. 7. This channel is cut away as indicated at 13 in 70 Fig. 7 for the purpose of receiving the sliding member 11 which moves therein and has its bearing against the front wall 14 of the drawer. Fastened rigidly to the front wall 75 of the drawer are the angles 15 and 16. One of these angles 15 is illustrated in side elevation in Fig. 5 and both of them are shown in front elevation in Fig. 3 and in cross section in Fig. 4. Each of these angles is provided with slots 17 and 18. At the rear 80 of these angles is placed the compressor 19. To this compressor is fastened four links 20, 21, 22 and 23. Each of these links extends forward and between the forward ends of the links 20 and 21 is supported the pin 85 24 and between the forward ends of the links 22 and 23 is supported the pin 25. The pin 24 passes through the openings 26 and 27 at the top of the sliding channel 12 and through the slots 18 in the angles 15 and 90 16. The pin 25 passes through the openings 28 and 29 at the bottom of the channel 12 and through the slots 17 of the angles 15 and 16. Pivotally fastened to the angle 15 are the links 30 and 31 and pivotally fastened 95 to the angle 16 are the links 32 and 33. As the angles 15 and 16 are rigid with the front of the drawer, the outer ends of the short links 30, 31, 32 and 33 will remain fixed. The inner ends of the short links are pivotally connected to the middle of the long links 20, 22, 21 and 23. When the handle 5 is moved up or down, it is obvious that the sliding member 11 will move down or up to 100 correspond therewith because of the engagement of the pin 8 with the sliding member. It will also be observed that the slots 9 and 10 are slightly turned up at the front so as to provide positive engagement with the pin 8 when the handle 5 is in the position shown 110

in Fig. 2. This holds the handle and the compressor locked in that position.

Fastened to the lower ends 35 and 36 in holes provided therefor, are the springs 37 and 38, the lower ends of which springs are fastened to the pin 25 carried in the channel 12. When the sliding member 11 is raised by placing the handle 5 in the position shown in Fig. 2, the springs 37 and 38 will be stretched, drawing with them the sliding channel 12 which in turn will raise the front ends of the links 20, 21, 22 and 23 which will re-act with the short links 30, 32, 31 and 33 forming a toggle therewith which will be partially straightened by this movement causing the compressor 19 to move rearwardly.

The compressor 19 is provided with a foot 40 that engages with the channel 41 provided in the bottom of the drawer by which it is held in position during its forward and back movement. It will be observed that the movement of the compressor 19 is comparatively limited. The movement is just sufficient to afford the necessary compression so as to hold the papers or photographic films or sheets of other material that may be held in the drawer, it being understood that the primary purpose of this invention is to provide a drawer that will hold photographic films tightly pressed together so as to exclude the air from between them and thus minimize the danger therefrom on account of fire. The films or papers are compressed against the movable compressor 42 which slides along the channel 41 and engages therewith and is held in place thereby in any well known manner.

The particular compressor illustrated herein, consists of an upright plate 43 having a flange 44 on the bottom thereof and having a foot 45 fastened thereto similar to the foot 40 illustrated in Fig. 3 which foot engages with the channel 41. Mounted on brackets 46 is the pin 47 on which is pivotally mounted the cam plate 48 which cam plate is pressed rearwardly at the top by means of the spring 49, the lower edge 50 of which cam plate engages with the bottom of the drawer for the purpose of holding the compressor 42 firmly in position. The plate 43 has a finger hole 51 struck up there in as is shown in Fig. 2 to facilitate the convenient operation of the compressor.

The compressor 19 can be operated to its compressing position by the handle 5 when the drawer is in any position provided the operator holds the drawer stationary but it can be automatically operated to compressing position when the drawer is pushed fully into the case that holds it. The operator can then force the compressor to its compressing and locked position by simply pushing down and back upon the handle 5.

When the drawer reaches the end of the

case, its further movement will be blocked and the handle can then be operated to move and lock the compressor. A quick pull up and out on the handle 5 will release the compressor 19 from the lock after which the drawer can be drawn out, all of which can be done by the operator using a single hand.

If a stop is provided in the path of the movement of the drawer, the drawer may be drawn forward until it encounters such stop after which the handle may be drawn up for the purpose of releasing the compressor. In the foregoing ways, the operation of the compressor by the handle is automatic. It will also be understood that the drawer may be mounted on slides interposed between it and the casing such as are shown in the patent to Ripson and Sampson, Nos. 884,525 and 884,526.

I claim:

1. In a filing case the combination of a drawer having a stationary front, a movable compressor mounted inside of said drawer adjacent to said front and means extending from said compressor to the outside of the drawer for moving said compressor. 90

2. In a filing case, the combination of a drawer having a stationary front, the compressor mounted to move inside of said drawer toward and away from said front, means extending through the front of the drawer for moving said compressor to compressing position. 95

3. In a filing case, the combination of a drawer, a pair of compressors therein, one of said compressors being movable longitudinally of the drawer, means for clamping said compressor in any desired position, the other compressor having a limited movement in the drawer and means for forcing the second compressor toward the first compressor. 100

4. In a filing case, the combination of a drawer, a pair of compressors therein, one of said compressors being movable longitudinally of the drawer, means for clamping said compressor in any desired position, the other compressor having a limited movement in the drawer and means for forcing the second compressor toward the first compressor, said means including a lever extending through the front of the drawer. 110

5. In a filing case, the combination of a drawer, having a front and a bottom rigid with each other, a compressor mounted to move along the bottom and standing parallel to the front of the drawer, a lever pivotally mounted outside of the drawer and extending inside, vertically sliding devices inside of the drawer operated by said lever, toggles connected to the compressor and operated by said vertically sliding devices for moving said compressor forward and back upon the operation of the lever. 125

6. In a filing case, the combination of a 130

5 drawer, a compressor mounted to slide therein, toggles connected to said compressor and the front of the drawer, a lever extending through the front of the drawer and connected to said toggles for moving the compressor forward and back.

10 7. In a filing case, the combination of a drawer having a fixed front and bottom therein, a pair of angles rigidly fastened to the front, a channeled frame sliding in said angles, a movable compressor in said drawer, toggles connected to said angles, said sliding frame and said compressor for moving the compressor forward and back and holding it parallel to the front of the drawer.

15 8. In a filing case, the combination of a drawer having a fixed bottom and front, a frame mounted to move vertically on said front, a compressor adjacent to said frame, toggles connected to said front and compressor and operated by said vertically moving frame for moving the compressor forward and back.

20 9. In a filing case, the combination of a drawer having a fixed bottom and front, a frame mounted to move vertically on said front, a compressor adjacent to said frame, toggles connected to said front and compressor and operated by said vertically moving frame for moving the compressor forward and back, a lever mounted in the front of the drawer having yielding connections

25 between said lever and said sliding frame through which the compressor is operated by said lever.

30 10. In a filing case, the combination of a drawer having a fixed bottom and front, a frame mounted to move vertically on said front, a compressor adjacent to said frame, toggles connected to said front and compressor and operated by said vertically moving frame for moving the compressor forward and back, a sliding member mounted in said sliding frame, springs connecting said sliding member to said sliding frame, a cam slot in said sliding member, a lever pivotally mounted in the front of the drawer and means on the same engaging with said cam slots by which said compressor can be moved and locked in its compressing position by the operation of said lever.

35 11. In a filing case the combination of a case, a drawer mounted to slide therein, a compressor mounted to slide in the drawer, means extending outside of the drawer for operating the compressor after the drawer has reached a fixed position.

In testimony whereof I affix my signature in presence of two witnesses.

RAYMOND G. BULLOCK.
